UNITED STATES PATENT OFFICE.

KURT ELTZE, OF MANNHEIM-KAFERTAL, GERMANY, ASSIGNOR TO BENZ & CIE., RHEINISCHE AUTOMOBIL- U. MOTOREN-FABRIK AKTIENGESELLSCHAFT, OF MANNHEIM, GERMANY, A CORPORATION OF GERMANY.

INTERNAL-COMBUSTION ENGINE.

Application filed December 16, 1924. Serial No. 756,211.

To all whom it may concern:

Be it known that I, KURT ELTZE, a citizen of Germany, and a resident of Mannheim-Kafertal, Germany, have invented certain new and useful Improvements in Internal-Combustion Engines, of which the following is a specification.

My invention relates to improvements in internal combustion engines, and more particularly in engines of the Diesel type in which the combustion of the fuel takes place during a part of a working stroke of the plunger and at uniform pressure, and in which an ignition chamber is provided for starting purposes and for atomizing the injected fuel during the normal operation of the engine. In engines of this type such as are now in use a tubular igniting member is located in the path of the fuel injected through an atomizing nozzle whereby the particles of fuel impinge against the incandescent wall of said igniting member. The igniting member communicates with the working chamber of the cylinder through fine apertures through which the fuel is thrown in a state of minute atomization into the main compression chamber of the cylinder. I have found that by thus injecting the fuel through narrow passages a pressure difference is produced between the cylinder and the ignition chamber before ignition takes place in the latter, whereby the charge is whirled around and fuel is driven into the ignition chamber, which interferes with complete combustion within the ignition chamber and results in the deposition of soot therein. Further, the said fine passages cause a loss of energy because they have a throttling action at times when such action is highly undesirable, such as after ignition of the charge.

The primary object of the invention is to provide an ignition member so constructed and arranged that the injected fuel will be completely atomized and thoroughly mixed with the air in the combustion chamber to provide an explosive charge for the cylinder.

Another object of the invention is to position the ignition member which fires the mixture during the normal running of the engine, in the passageway connecting the ignition chamber with the combustion chamber, and to provide through said member a

passageway of improved shape or cross section opening into the combustion chamber in a plurality of orifices, one of which is centrally located and of relatively larger diameter. Preferably the enlarged orifice is located in position for being closed by a plug 55 provided on the plunger of the engine and having a length sufficient to close the aperture until the injection of the fuel is finished, which is the case with the crank at an angle of 60°. Therefore, the atomization of the 60 fuel is effected exclusively through the small 65 passages of the igniting member, and after the injection and combustion have been completed it is immaterial as far as expansion is concerned whether or not the ignition and 70 working chambers communicate through the said orifice.

For the purpose of explaining the invention an example embodying the same has been illustrated in the accompanying drawing 75 showing a section of the upper part of the cylinder of the engine.

In the example shown in the drawing the head *d* of the cylinder is formed with an ignition chamber *a* adapted to have fuel injected into the same through an atomizing nozzle *b* when the working plunger *h* is substantially in its upper dead center. Ignition for starting the engine is obtained by means of a resistance wire or coil *n* adapted 80 to be brought to incandescence by connecting it to a source of electric current. After the spray of fuel has been ignited by this incandescent wire, and when the main igniting member *c* has reached the proper 85 temperature, the electric current to the coil *n* is interrupted, and the said member *c* will fire the explosive mixture during the normal running of the engine. The specific arrangement of this igniter *n* is not claimed in 90 the present application, but is included in the claims of my co-pending application Serial No. 3,071 filed in the United States Patent Office on January 17, 1925. Within the reduced bottom part of the said chamber 95 there is an igniting member in the form of a bushing *c* fitting in the said bottom part and providing an annular chamber *e* therewith the size of which is such as to insure 100 heating of the bushing at the desired temperature. At its bottom the bushing *c* is provided with passages *f* for the injection 105 of the fuel from the chamber *a* into the work-

2
ing chamber of the cylinder. In addition the said bottom of the bushing is provided with an axial opening *m* of large diameter which is adapted to be closed by an axial 5 plug *i* provided on the plunger *h* and loosely fitting in the said aperture. The length of the said plug is such that the aperture is closed while the plunger *h* moves from its upper dead center down to an angle of the 10 crank of about 60° , when the injection of the fuel is finished.

Through the passages *f* the fuel ignited within the ignition chamber *a* is injected by preliminary explosion into the main compression chamber where it is burnt by 15 hot air.

By providing the aperture *m* in the bottom wall of the bushing *c* the said bushing must be made with a comparatively large 20 diameter, and the said diameter is sometimes 25 larger than is desirable in view of the whirling of the fuel and air within the ignition chamber, said whirling being caused by the difference of pressure between the ignition chamber and the working chamber of the cylinder when the working plunger is in its upper dead center and before the ignition within the ignition chamber has been started. If the bottom part of the bushing *c* is narrow 30 the combustible mixture rushes into the ignition chamber at high velocity thus producing a thorough mixture of fuel and air within the ignition chamber. If, however, the bottom part of the bushing is too broad 35 a pure combustible mixture is produced within the ignition chamber. For this reason I prefer to reduce the bushing *c* in cross-section at a part above the plug *i*, as is shown at *k*.

40 I claim:

1. An internal combustion engine comprising a cylinder, a plunger movable in said cylinder, a cylinder head, a combustion chamber, an ignition chamber, a passageway between said chambers, a nozzle mounted in

the wall of the ignition chamber and adapted to eject fuel into the same and said passageway, an igniting bushing mounted in said passageway and having a tapering bore, means forming a plurality of orifices at one end of said bushing, and means for closing one of said orifices during the injection of fuel into said passageway. 50

2. In an internal combustion engine having a cylinder, a piston moving in said cylinder, a combustion chamber, an ignition chamber and a passageway between said chambers, means for injecting fuel into said passageway, an igniting bushing mounted in said passageway and provided with an internal bore of tapering cross-section and a restricted throat intermediate its ends, means forming a plurality of orifices between said throat and combustion chamber, and means on the piston for closing one of said orifices 60 when said piston is in a predetermined position. 65

3. An internal combustion engine comprising a cylinder having a compression chamber, an ignition chamber, means forming a passageway between said chambers, an ignition bushing mounted in said passageway, said bushing being provided with an axial bore of tapering cross-section extending 70 from one end and terminating in a throat intermediate the ends, means forming a plurality of angularly arranged orifices and a large central orifice between the said throat and combustion chamber, and a plug mounted on the piston and adapted to extend 75 through said central orifice and spaced from said throat when the piston is at the top of the cylinder. 80

In testimony whereof I hereunto affix my signature in the presence of two witnesses.

KURT ELTZE.
